UNITED STATES PATENT OFFICE

2,304,660

APPARATUS FOR MOLDING BUILDING BLOCKS

Paul E. Scott, Chicago, Ill.

Application December 30, 1940, Serial No. 372,267

4 Claims. (Cl. 25—41)

My invention relates to improvements in apparatus for manufacturing building blocks or similar objects.

My invention relates more particularly to an improved apparatus for making building blocks of the type normally used for the construction of cisterns, cesspools, sewer entrances and other types of building wherein cement or other blocks are provided of an arcuate shape and with interconnecting edges, although it will be understood that any desirable type or shape of block may be constructed with my apparatus.

The principal object of the present invention is to provide an apparatus for manufacturing blocks of the type described that is efficient in operation and capable of producing a highly improved type of block.

A further object of the invention is to provide a machine or apparatus of the type described whereby unskilled artisans, by the use of the machine, may make such blocks easily, accurately and in large capacity.

A further object of the invention is to provide an improved process of manufacturing concrete blocks or blocks of a similar nature whereby the steps of removing the block from the mold are practically eliminated and a simple method of removing the mold from the blocks is substituted.

A further object of the invention is to provide an improved method of the type described which includes the steps of delivering the concrete or other mixture to a hopper, moving the hopper over a mold, vibrating and packing the material into the mold to construct a block of desired strength and density, and then removing the mold by withdrawing the side walls from the formed block, permitting the operator to pick up the support upon which the block has been molded, and place the same in a drying room.

A further object of the invention is to provide an improved apparatus for carrying out the above described steps cheaply and efficiently.

A further object is to provide in a block manufacturing apparatus, improved treadle-controlled mechanism for horizontally moving the side walls of the mold away from a block after the same has been formed.

A further object is to provide mechanism of the type described that is easily adapted to changes in shape or size so that a number of different size and shaped blocks may be made by the same machine.

Other objects and advantages will be more apparent from the following description wherein

reference is had to the accompanying three sheets of drawings, upon which

Fig. 1 is a front elevational view of one embodiment of an apparatus for carrying out my improved process;

Fig. 2 is a vertical cross-sectional view through the machine taken generally on the line 2—2 of Fig. 1;

Fig. 3 is a plan sectional view showing my improved mold and associated parts and is taken generally on the line 3—3 of Fig. 2;

Fig. 4 is a fragmentary sectional view taken in the plane of Fig. 1, showing portions of my improved mold and the mechanism for removing the side walls from the molded block in a changed position;

Fig. 5 is a vertical sectional view taken on the line 5—5 of Fig. 3, showing a block marking device; and

Fig. 6 is a front perspective view of one type of blocks which can be manufactured by the use of my improved process and apparatus.

In the embodiment of the invention which I have chosen to illustrate, I have shown generally a vertical frame constructed of the upright angle members 10 and 12 suitably connected together adjacent their lower ends by the cross-frame members 14. The frame members 10 and 12 may continue upwardly from the cross members 14 adjacent the lower end of the same and be provided with a platform or table portion 16 suitably fastened within the four angle members 10, 10, 12 and 12. The mold 18 may be positioned upon the table 16 and directly below a stationary horizontal wall 20 which forms a base for a movable auxiliary hopper 22. A pair of vertical side walls 24 and 26 may extend upwardly upon the sides of auxiliary hopper 22 and provide enclosing side walls for the hopper 26 to which the mixed concrete or other material is adapted to be delivered. The hopper 26 is further formed with the front wall 28, the inclined wall 30 and the back wall 32, forming a rectangular opening which coincides with the opening 34a to the chamber 34 in the auxiliary hopper 22.

The material from which the blocks are to be formed may be mixed and then placed upon an endless conveyor 36 which generally comprises a pair of spaced chains connected by angle members 38. A stationary platform 40 terminating at a point 42 may be positioned under the endless conveyor so that material may be carried upwardly and dropped from the conveyor at the point 42 into the hopper 26. The chains of the endless conveyor may be trained about sprocket

wheels 44 which are mounted upon a horizontal shaft 46 supported in suitable bearings in the uprights 48 and 50. The shaft 46 may be driven by a chain 52 trained over a sprocket wheel 54 keyed to the shaft 46, the chain being driven from a sprocket wheel 56 keyed to the shaft 58. Shaft 58 is in turn driven by a sprocket wheel 60 which receives a chain drive 62 from a sprocket wheel 64 keyed to the shaft 66. Shaft 66 may be mounted in a suitable bearing 68 on a back wall member 70 connected to the uprights 10 and 12. A flywheel 72 is mounted upon the shaft 66 being driven by a belt 74 from a source of power such as an electric motor 76 supported on a suitable base 78 adjacent the lower end of the machine.

I provide means for reciprocating the auxiliary hopper 22 on the platform 20 from the position shown in Fig. 2 to a position above the mold 18 and back. This mechanism may include a carriage for the same comprising the rollers 80 which ride upon the tracks 82 and a drive for the same. The driving means consists of a friction disc 84 positioned between a pair of vertically disposed driving discs 86 mounted on shaft 58. The disc 84 is mounted on the end of a screw-threaded rod 88 which screw-threadedly engages a block 90 rigidly secured to the auxiliary housing 22; thus, when the rod 88 is angularly pivoted about its bearing 92 to bring the friction disc 84 in contact with one or the other of the driving discs 86, the rod 88 will be turned and by means of its connection with the block 90, the auxiliary housing 22 will be moved forward or back as desired. A suitable stop 94 is provided for the extreme back position of the hopper, and stop members including plates 96 are provided at the forward end of the machine to permit the alignment of the hopper chamber 34 over the mold 18. The lever 98, through suitable mechanism, is connected to the bearing 92 to move the friction disc 84 to the right or left to effect the back or forward motion of the auxiliary hopper. The auxiliary hopper 22 is provided with a top wall 22a having the opening 34a therein adapted in its initial position to be aligned with the opening in the hopper 26, the wall 22a being provided so that when the hopper 22 is moved forward, the lower end of hopper 26 will be closed.

As thus far described, mechanism has been provided for conveying a mixture such as concrete or other products from which blocks are manufactured, to a hopper 26, from where in certain positions, the material will pass into the chamber of hopper 22 in position to be moved forward to a point above the mold 18. Assuming now that the mechanism has been moved forward to a position above the mold 18, a charge of material will then be permitted to flow into the mold 18 to take the shape of the finished block. In order to pack the material into a satisfactory homogeneous mass in the mold 18, to eliminate air bubbles and other imperfections in the finished block, I have provided a vibrating mechanism which may include a shaft 100 having an offset weight thereon so that when the same is revolved at a high rate of speed a synchronous vibration will be set up. The shaft 100 may be driven from a suitable motor 101 by means of a chain 103 trained over sprockets 105 on the motor and 107 on the shaft 100. This vibration may be transmitted to the table 16 by a rigid connection between the housing 102 and upright arm 104, and a bracket 106 connected to the lower side of the table 16. To further insure the construction

of a more efficient building block, I have provided a weight member 108 carried by vertical arms 110 which may be lowered into the chamber 34 when the same is aligned with the mold 18. A hand lever 112 pivoted at 114 to a suitable upright, may be connected to the framework formed by the arms 110 so that when desired the lever 112 may be released from its support 116 and the weight 108 may be dropped upon the top of the material in chamber 34, thus driving the same into the mold 18 to create a more perfect and more homogeneous block.

As thus far described, it can be seen that the building block, by vibration and pounding, has been formed in the mold 18 to a desired shape and consistency. The auxiliary hopper 22 may now be returned to its original position, and the block is ready to be removed from the mold and placed in a drying room.

Referring now to Figs. 3 and 4, the mold 18 may include a bracket member having a rearwardly extending arm 118 which is pivotally mounted upon the table 16 by a bolt member 122. The mold itself may include the left and right wall portions 114 and 116 and the connected back and front portions 118 and 120. In order to remove the block B from the mold, the handle 122 is grasped and the latch member 124 is pivotally swung to release it from the left wall 114. With this disconnection the bracket which includes the back and front walls and the connecting portion 119 may be swung about the pivot 112 away from the formed block. The side walls 114 and 116 are then swung away from the block B in a manner to be described and the completed block positioned upon a board or other suitable platform 126 may be picked up and carried to a drying room.

The mechanism for swinging the side walls outwardly will now be described. This mechanism may include a pair of angular slots 128 and 130 in the table 16 and bracket members 132 and 134 extending therethrough and connected to the side walls 114 and 116. The bracket members 132 and 134 which are identical, may extend downwardly through the slots 128 and 130, be pivotally mounted upon rods 136 and 138, and carry bolt members 140 and 142 adjacent their lower ends. Each of the bolt members 140 and 142 is adapted to be engaged in a desired notch 144 in an arm 146 which is connected by a pivoted bolt 148 adjacent one end to a T-shaped arm 150. The arm 150 may be pivotally connected at its lower end by the pin 152 to a foot treadle lever 154 pivotally mounted upon a rod 156 and provided with a treadle portion 158. The rod 156 may be fixedly secured in a suitable bracket on the lower frame member 14. The rods 136 and 138 may be supported in a pair of brackets 160 and 162 secured below the table portion 16. Each of the brackets is formed with a plurality of notches 164 so that the rod members may be received in any one of a plurality of notches for a purpose which will be hereinafter described.

With the construction thus shown, after a block has been formed in the mold 18 and it is desired to remove the side walls, the latch 124 is unlatched and the bracket 110 is swung to the dotted line position shown in Fig. 3 as previously described. By stepping upon the foot treadle 158 arm 150 will be raised thus swinging the brackets 132 and 134 about their pivots 136 and 138 and moving them away from the edges of the block. The block is now free to be removed upon it.

platform 126. The side walls are all returned by reversing the operations herein described in preparation for receiving the material to form the next block. Minute adjustment is obtained for positioning the side walls 114 and 116 by the bolt members 166 and 168 which may be screw-threadedly adjusted to bear against the edges of the platform 126.

In the event that a larger size block is desired than the one shown in the drawings, the side walls 114 and 116 may be moved outwardly by lifting the brackets 132 and 134 and their cross-rod 136 and 138 out of the notches 164 in which they are positioned, and moving them outwardly. In the same manner, the bolt members 140 and 142 will have to be moved outwardly in the notches 144 of the arms 146. In addition, a new bracket 110 with longer arcuate walls 118 and 120 would of course be provided. The table 16 is provided with a plurality of openings 16a to receive the bracket 110 when different size blocks are made, especially blocks which have parallel side walls formed on a different radius.

From the above and foregoing description it is believed to be clear to those skilled in the art that with the construction shown and by the use of a plurality of mold brackets, arcuately shaped blocks of several different sizes can be made with the same machine. If a different type of edge interlock connection is desired, different brackets 132 and 134 can be provided with the desired edge formations in the walls 114 and 116. The rods 136 and 138 are provided with L-shaped latch members 137 which have a leg adapted to engage under a suitable ledge 139 on the brackets 160 and 162 when the machine is in operation. The latches are normally held in this position by spring members S.

In order to provide identifying indicia upon the completed blocks, such for example as to indicate one of three or four sizes, I have provided in the wall 120 of the mold, a plug member 172 having a shoulder 174 and a compression spring 176 normally holding the plug in the position shown in Fig. 5. The housing 178 encloses the same except for a button 180 which extends outwardly therefrom. When blocks of a certain size are being made and it is desired to mark them to identify the same for workmen who may use them later, after the block has been molded the operator of the machine may push in on the button 180 and with the plug 172 form an indentation such as B8 shown in Fig. 6. Upon releasing pressure upon the button 180 the plug will be sprung back into the wall 120 so that the mold bracket may be swung away from the block as previously described. It is of course understood that various sizes of mold brackets will carry different identifying marks, such for example as two openings, or openings of different shapes so that they are easily identifiable.

While I have illustrated and described a specific embodiment of my invention, it will be apparent to those skilled in the art that changes and modifications may be made in the exact detail shown, and I do not wish to be limited in any particular; rather what I desire to secure and protect by Letters Patent of the United States is:

1. In a machine for manufacturing molded building blocks that has means for conveying material from which the blocks are constructed to a hopper on said machine and means for moving the hopper forward to overlie a mold, a mold for blocks comprising a pivotally mounted bracket having parallel front and back walls, said walls connected together at one edge, said mold having edge walls adapted to be pivotally swung away from a block when molded, and a foot treadle operated mechanism attached to said side walls for effecting said motion.

2. In a machine for manufacturing molded building blocks that has means for conveying material from which the blocks are constructed to a hopper on said machine and means for moving the hopper forward to overlie a mold, a mold for blocks comprising a pivotally mounted bracket having parallel front and back walls, said walls connected together at one edge, said mold having edge walls adapted to be pivotally swung away from a block when molded, and a foot treadle operated mechanism attached to said side walls for effecting said motion, said mechanism including a pair of bracket having spaced notches to receive pivots and pivotally mounted levers mounted in said notches.

3. In a machine for manufacturing molded building blocks that has means for conveying material from which the blocks are constructed to a hopper on said machine and means for moving the hopper forward to overlie a mold positioned on a removable platform on said machine, a mold for blocks comprising a pivotally mounted bracket, front and back walls and edge walls, and means associated with said edge walls for moving the same horizontally away from a formed block on said removable platform.

4. In a machine for manufacturing molded building blocks that has means for conveying material from which the blocks are constructed to a hopper on said machine and means for moving the hopper forward to overlie a mold positioned on a removable platform on said machine, a mold for blocks comprising a pivotally mounted bracket, front and back walls and edge walls, and means associated with said edge walls for moving the same horizontally away from a formed block on said removable platform, said means including a bracket adapted to swing in a horizontal plane about a pivot, said bracket being connected to certain of said walls.

PAUL E. SCOTT.
